ELECTRIC HOIST

Christopher H. Schramm, Muskegon, Mich., assignor to Manning, Maxwell & Moore, Inc., Muskegon, Mich., a corporation of New Jersey

Application September 6, 1938, Serial No. 228,511

6 Claims. (Cl. 254—168)

The invention relates to electric hoists and has particular utility as applied to hoists of the portable type.

One object of the present invention is to provide an extremely compact electric hoist of minimum weight and over-all dimensions. In particular this object is accomplished by a novel arrangement or disposition of the parts of the hoist by means of which they are symmetrically disposed about a central vertical line of support in such manner as to require a minimum amount of counterweighting and to utilize to a maximum extent all available space within the housing of the hoist for the accommodation of such elements as the hoist brake and its associated parts.

Further objects and advantages of the invention will become apparent as the following description proceeds taken in connection with the accompanying drawings in which:

Figure 1 is a general perspective view of an electric hoist embodying the invention.

Figs. 2 and 3 are respectively enlarged transverse and longitudinal vertical sectional views of the hoist shown in Fig. 1 illustrating particularly the brake mechanism and associated parts with the remaining elements of the hoist indicated in dot dash lines.

Figs. 4 and 5 are respectively enlarged vertical transverse and longitudinal sectional views, similar to Figs. 2 and 3, of a hoist embodying a modified form of brake mechanism.

The invention has been shown herein (Fig. 1) for purposes of illustration and explanation of its various novel features, as embodied in a portable hoist which is adapted to be supported as a unitary structure from a single suitable supporting device such as a hook 10. A revoluble hoist member, such as a chain pinion 11 (Fig. 3), is located directly below the hook 10 so that the vertical force applied to the hoist by a load on the hoisting member 11 acts in a vertical line passing directly through the hook 10 without any skewing or tilting of the hoist structure. A hoist line such as a roller chain 12 is reeved over the chain pinion 11. To identify the other general elements of the hoist in a few words, it includes a generally flat vertically disposed gear case 13, to the top of which the hook 10 is made fast and on the lower portion of which the pinion 11 is mounted. Also included in the hoist is a horizontally disposed electric driving motor 14 bolted to a complementary cylindrical extension 15 fashioned on one side wall of the gear case, and connected through a suitable speed reduction gearing within the gear case to the chain pinion 11.

The gear case and motor arrangement described above is not in and of itself my invention, but is described and claimed in the copending application of Preston Whitcomb and Ralph E. Smith, Serial No. 228,509 filed September 6, 1938. In accordance with one aspect of my invention, the over-all dimensions and weight of the hoist have been markedly reduced by utilizing the space between the end of the motor rotor and the gearing 10 within the case 13 to accommodate a brake mechanism designated generally by the numeral 16. By so locating the brake mechanism substantially on the vertical center line of the hoist which passes through the hook 10 and hoisting member 11, a symmetrical or balanced distribution of the weight of the brake mechanism is achieved as well as utilization of what would otherwise be wasted space within the hoist structure. In view of the center line location of the brake mechanism, it is unnecessary to provide any substantial counterweighting on the gear case to counterbalance the brake mechanism as would be the case if it were, for example, mounted on the outboard end of the motor shaft. Also, a standard motor shaft can be utilized as contrasted with a special shaft with an outboard extension to receive the brake in the event that the brake is mounted on the outer end of the motor. Furthermore, the brake mechanism is housed by the extension 15 on the gear case so that it is thoroughly protected.

Turning now to a more detailed consideration of the various parts of the hoist illustrated in Figs. 1, 2 and 3, it will be seen that the driving motor 14 is of generally conventional form (Fig. 2) and includes a stator 17 as well as a rotor 18 carried by a horizontal shaft 19. The motor is housed by a generally cylindrical frame or casting member 20 provided with the usual end bell 21 at its outer end. The open inner end of the motor casing 20 is fitted on the cylindrical gear case extension 15 and closed thereby. Through bolts 20* secure the motor in position. In this position of the motor the shaft 19 extends within the gear case 13 and is journaled in a sleeve bearing 22 fashioned in the gear case itself rather than in the motor frame. The outer end of the motor shaft is journaled in a bearing 23 carried by the end bell 21.

The gear case 13 may be conveniently fashioned as a casting and includes a cup-shaped part or shell 24 having a vertically disposed generally flat bottom wall or web 25 on the outer face of which the cylindrical extension 15 is integrally formed (Fig. 3). A second integral extension 26

carries the revoluble hoisting member 11. This hoisting member or pinion 11 is connected in driven relation with a pinion 27, on the inner end of the motor shaft 19, by a suitable speed reduction gearing housed within the gear case 13. The outer end of the gear case is closed by a generally flat end member 28 bolted to the cup-shaped casting 24.

The driving motor 14 is controlled by a reversing controller 29 fixed to the lower side of the motor frame by a bracket 38. This controller embodies a rock shaft 31 oscillatable from a central neutral position, indicated by the dot dash line marked N in Fig. 2, alternatively to either hoisting or lowering positions indicated respectively by the dot dash lines marked H and L. When the controller 29 is in its neutral position, the driving motor is deenergized and while in the respective hoisting and lowering positions the motor is energized for corresponding directions of rotation. Preferably, the controller 29 and the brake mechanism 16 are so interlocked that the brake will be released automatically whenever the controller is shifted to either hoisting or lowering position, but will be applied when the controller is in its neutral position, thereby preventing a gravitational descent of any load on the hoist when the motor is stopped.

The brake mechanism 16 has been shown as being of the mechanical type and in the particular form illustrated in Figs. 2 and 3 embodies a brake drum 32 keyed to the projecting inner end portion of the motor shaft 19. The brake mechanism is thus housed within the cylindrical extension 15 on the gear case and occupies a clearance space between the motor rotor and speed reduction gear which would, in any event, have to be provided in order to attain a symmetrical weight distribution of parts of the hoist about its vertical center line. Cooperating with the rotatable brake drum 32 are a pair of non-rotatable brake elements or friction shoes 33 pivoted on the gear case web 25 by pins 34 for movement into and out of engagement with the brake drum. The brake shoes 33 are normally urged into frictional engagement with the brake drum by a helical tension spring 35 anchored at its ends to the opposed swingable ends of the brake shoes.

In order to accomplish automatic actuation of the brake mechanism 16 in timed relation with the movement of the motor reversing controller 29, integral laterally extending arms 36 are fashioned on the pivoted brake shoes 33. These arms extend through suitable apertures 37 in the gear case extension 15 and are provided with offset (see Fig. 3) lower ends 36^a embracing a cooperating actuator cam 38 fast on the controller rock shaft 31. When the cam 38 is in its central or neutral position shown in Fig. 2, the brake shoes 33 are permitted to engage the brake drum 32 under the bias of the spring 35. However, when the cam 38 is oscillated either clockwise or counter-clockwise to hoisting or lowering position, projections 38^a engage abutments 39, adjustably threaded in the offset lower ends 36^a of the brake shoe arms, and push the brake shoes apart out of engagement with the brake drum, thereby releasing the brake.

An actuator mechanism for the controller and brake cam 38 has been shown herein, which in the particular arrangement illustrated, embodies a round disk or pulley 40 integral with the cam 38. A control cord is passed over this pulley and made fast thereto at 41 with its ends 42 and 75

43 depending from opposite sides of the pulley. With this arrangement the operator can shift the controller 29 to hoisting position by pulling on the cord end 42, and similarly to lowering position by pulling on the cord end 43. Throughout the oscillation of the controller rock shaft 31, the depending ends of the control cord remain in substantially vertical position and tangential to the pulley 40. As a result, the length of the lever arm between the line of action of the force applied to the depending cord end and the center of the shaft 31 remains substantially constant. Consequently, there is no appreciable variation in the force required to shift the controller throughout its entire arc of movement. This is to be contrasted with the action in the event that a horizontal cross arm is fixed to the controller rock shaft with control cords depending from its opposite ends and in which case the force required to move the rock shaft increases with its displacement from its neutral position. This feature of preventing an increase of force required for shifting the controller is particularly advantageous when the controller is also used to actuate a mechanical brake mechanism such as that heretofore described. With such a brake mechanism, if the brake is released before the motor is energized by closure of the controller contacts, the load on the hoist will start to descend by gravity with consequent possible damage to the motor and its associated parts. Such undesirable operation is much more likely to take place in the event that a greater force is required by the operator to shift the controller into its final contact closing position. With the pulley arrangement herein disclosed, this possibility is largely obviated.

If desired, an arrangement may be provided for automatically stopping the hoist at the upper and lower extremities of the movement of the hoist chain 12. In the construction illustrated, 40 one end of the chain 12 is secured to the side of the gear case 13 by a yieldable tension spring 44 (Fig. 1) and then reeved over the pinion 11 with a suitable load supporting device such as a load hook 45 secured to the free end of the chain. In order to stop the hoist automatically at the end of its lowering movement, a lever 46 is pivoted on the gear case 13 by a pin 47 and disposed 45 within the loop in the chain 12 between the spring 44 and pinion 11. When the controller is turned to its lowering position a lug 48 on the cam 38 contacts the free end of the lever 46 and pushes it downward. When the chain 12 reaches its extreme lowering position, however, the loop in the chain embracing the lever 46 is drawn up so that the lever is returned to its horizontal position and the controller thereby also returned to its neutral position to stop the motor. A similar stop lever 49 (Fig. 2) is disposed on the opposite side of the hoisting pinion 11 being also pivoted on the gear case 13. This lever 49 is arranged to be contacted by an abutment 51 (Fig. 1) on the shank of the load hook 45 in the extreme hoisting position of the chain. When the cam 38 is shifted to its hoisting position, a lug 52 (Fig. 2) thereon engages the free end of the stop lever 49 and pushes it downwardly. Then when the abutment 51 contacts the lever and returns it to its horizontal position, the cam and associated controller 29 are also returned to neutral position to stop the driving motor 14.

The operation of the hoist will in general be understood from the foregoing description. As a brief résumé, let it be assumed that the operator

wishes to lift a load. In such case the load is attached to the hook 45 and the operator pulls down on the control cord 42, thereby tilting the controller rock shaft 31 until the longitudinal center line of the cam 38 occupies the position indicated by the dot dash line H in Fig. 2. In such position of the controller shaft and cam the driving motor 14 is energized for hoisting and the brake 16 is released. To stop the hoisting operation, the operator simply releases the cord 42 so that a centering spring (not shown) in the controller 29, pulls the rock shaft 31 back to neutral position, thereby open-circuiting the driving motor. At the same time the cam 38 releases the brake arms 39 so that the brake 16 is applied to hold the load suspended. Similarly to lower the load hook 45, the operator pulls down on the control cord 43 thereby shifting the controller rock shaft to connect the motor 14 for lowering and to release the brake 16 simultaneously. Again the hoist is stopped at will by simply releasing the control cord so that the controller rock shaft may return to its neutral position.

Figs. 4 and 5 illustrate a modified form of electric hoist embodying the invention. The construction shown in these figures is generally the same as that of Figs. 1 to 3, inclusive, except that a brake mechanism 53 of the electromagnetically actuated type is used rather than a mechanical brake such as the brake 16. The same reference numerals have been used in Figs. 4 and 5 to indicate identical parts and a repetition of the description of these parts is believed to be unnecessary. As to the brake mechanism 53, which constitutes the changed element of the combination, it includes a rotatable element or brake drum 54 keyed to the projecting inner end of the motor shaft 19. This brake drum is located within the cylindrical extension 18 on the gear case just as in the case of the brake drum 32 of the brake mechanism 16 previously described. In the present instance, however, the cooperating non-rotatable brake element has been shown in the form of a flexible brake band 55 anchored at one end to the adjacent face of the gear case web 28 by a pin 56. The free end of the brake band is secured to one end of a pin 57 carried by a link 58 pivoted on the gear case extension 18 by a pin 59. A helical compression spring 60 interposed between the forward end of the pin 57 and a fixed bracket 61 serves to normally bias the pin 57 to a position in which the brake band 55 frictionally engages the brake drum 54. In order to release the brake the link 58 is pivoted in a counterclockwise direction (as viewed in Fig. 4) thereby compressing the spring 60 and moving the end of the brake band 55 away from the drum. In order to adjust the tension on the brake band 55, the pin 57 is threaded in a suitably tapped hole 57a in the link 58 so that the pin 57 may be adjusted axially with respect to the link. A lock nut 57b holds the pin in its adjusted position.

An actuating solenoid, designated generally by the numeral 62, has been provided for moving the brake operating link 58. This solenoid includes the usual stationary energizing winding within a casing 63 and an axially movable plunger type armature 64. This plunger is connected with the outer end of the link 58, which extends through a suitable aperture 58a in the side of the gear case extension 18, by a pin and slot connection 65. When the solenoid is de-energized, the armature 64 occupies the position shown in Fig. 2 in which the brake is engaged

due to the bias of the spring 60. Upon energization of the solenoid, however, the armature 64 is pulled downwardly, thereby oscillating the link 58 in a counterclockwise direction and releasing the brake. The control circuit for the solenoid 62 is connected to the motor controller 29 so that the solenoid will be energized to release the brake 53 whenever the driving motor 14 is energized. The same synchronization of brake and motor operation is thus achieved electrically as was attained by the mechanical interconnection described above with respect to the hoist shown in Figs. 1 to 3, inclusive.

Although certain particular embodiments of the invention have been shown and described in some detail for purposes of illustration, there is no intention to thereby limit the invention to such embodiments, but on the other hand the appended claims are intended to cover all modifications and alternative constructions within the spirit and scope of the invention.

I claim as my invention:

1. An electric hoist comprising, in combination, an electric driving motor embodying a horizontally disposed generally cylindrical casing open at one end and closed at the other end and a rotor shaft projecting out through said one open end, a gear case having a generally vertical web therein with a complemental cylindrical extension thereon secured to the open end of said motor casing to close the same, means in said gear case for journaling the projecting end portion of said motor shaft, means including a hook fixed to the top of said gear case for suspending said gear case and motor as a unitary structure, a hoist member revolvably mounted on said gear case below said motor and substantially in vertical alignment with said hook, a speed reduction gearing in said gear case drivingly connecting said motor and said hoist member, and a brake for said motor including a rotatable brake drum fast on the portion of said motor shaft within said cylindrical extension on said gear case and a cooperating fixed brake element housed within said cylindrical extension, the weight of said hoist being disposed symmetrically about a vertical line passing through said supporting means and said hoisting member.

2. An electric hoist comprising, in combination, an electric driving motor, embodying a horizontally disposed generally cylindrical casing open at one end and closed at the other and a rotor shaft projecting out through said one open end, a gear case having a generally vertical web therein with a complemental cylindrical extension thereon secured to the open end of said motor casing to close the same, means on said gear case for journaling the projecting end portion of said motor shaft, means for suspending said motor and said gear case as a unitary structure and attached to such unitary structure at a point adjacent the line of juncture between said motor casing and gear case, a hoist member revolvably mounted on said unitary structure below said motor and substantially in vertical alignment with said last named means, a speed reduction gearing in said gear case drivingly connecting said motor and hoist member, and a brake for said motor including a rotatable element fast on the projecting end portion of said motor shaft and a cooperating fixed element, the weight of said hoist being disposed symmetrically about a vertical line passing through said supporting means and said hoisting member.

3. An electric hoist comprising, in combina-

tion, an electric driving motor embodying a horizontally disposed generally cylindrical casing open at one end and closed at the other and a rotor shaft projecting out through said one open end, a gear case having a generally vertical web therein with a complementary cylindrical extension thereon secured to the open end of said motor casing to close the same, means on said gear case for journaling the projecting end portion of said motor shaft, means for suspending said motor and said gear case as a unitary structure and attached to such unitary structure at a point adjacent the line of juncture between said motor casing and gear case, a hoist member revolvably mounted on said unitary structure below said motor and substantially in vertical alignment with said last named means, a speed reduction gearing in said gear case drivingly connecting said motor and hoist member, a brake for said motor including a rotatable element fast on the projecting end portion of said motor shaft and a cooperating fixed element, a reversing controller for said motor disposed on the exterior of said unitary structure and including an oscillatable control shaft, said cylindrical extension on said gear case having an aperture therein, and means extending through said aperture for operatively connecting said brake and control shaft.

4. An electric hoist comprising, in combination, a revolvable hoisting member, a reversible electric motor connected in driving relation with said hoisting member, a reversing controller for said motor including a shaft oscillatable from a central neutral position in opposite directions to respective hoisting and lowering positions, means including a brake for releasably holding said hoisting member against rotation, a cam on said controller shaft, means including a cam follower yieldingly urged into engagement with said cam for releasing said brake only when said shaft is shifted from neutral position into hoisting or lowering positions, manually operable means for oscillating said shaft, a hoist-line reeved over said hoisting member and disposed with one end secured to a member rigid with said motor and the other depending from said hoisting member and carrying an abutment, limit control means including two vertically shiftable members disposed on opposite sides of said hoisting member, one of said vertically shiftable members projecting through the loop in the fixed end of the line to be raised by it at the extremity of lowering movement the other of said vertically movable members being disposed in the path of said abutment and above the same to be raised by it at the extremity of hoisting movement, and

means including projections on said cam engageable respectively by said vertically movable members for returning said shaft to neutral position at the respective extremities of movement of said hoist line.

5. In a portable electric hoist, the combination of an electric motor and gear case disposed side by side in spaced relation with a horizontal, generally cylindrical, rigid extension on the gear case 10 bridging the gap between them, said motor being generally axially aligned with said extension and fixed thereto, shafting extending from said motor through said extension into said casing, a brake mechanism housed within said extension and operatively connected to the portion of said shafting therein, supporting means fixed to the top of said extension and a hoisting member rotatably mounted on the opposite or lower side of said extension in substantial vertical alignment 15 with said supporting means, and a speed reduction gearing in said casing operatively connecting said shafting and said hoisting member, the weight of the various elements being substantially symmetrically distributed about a vertical center line passing through said supporting means and hoisting member.

6. A portable electric hoist having in combination, a rigid supporting structure comprising a central ring member adapted to be supported with its axis horizontally disposed and a gear casing rigid with one side of the ring member and forming therewith a unitary structure, said ring member being open at the side opposite said gear casing, an electric motor mounted upon 30 said ring member and having a casing with one end in open communication with the open side of said ring member, said motor having a rotor with a shaft projecting through said ring member into said gear casing, a bearing for said 35 motor shaft carried by said unitary structure, a hoisting member journaled in the unitary structure at the lower side of said ring member on an axis disposed parallel with the motor shaft, reduction gearing in said casing operatively connecting said motor shaft and said hoisting member, 40 a brake drum fast on the motor shaft between said rotor and said bearing, a pair of brake members disposed within said ring member and pivotally mounted on said unitary structure for movement toward and from opposite sides of said brake drum, a reversing controller 45 for said motor including a manually operable member, and means on said manually operable member operatively connected with said pivoted 50 brake members to actuate the same.

CHRISTOPHER H. SCHRAMM.
